VARIABLE RESISTOR

Shunzo Oka, Hirakata, Osaka, Japan, assignor to Matsushita Electric Industrial Co., Ltd., Osaka, Japan

Filed July 5, 1972, Ser. No. 269,252

Term of patent 14 years

Int. Cl. D13—03

U.S. Cl. D26—1 D

FIG. 1

FIG. 2

FIG. 3

FIG. 4

FIG. 1 is a side elevational view of a variable resistor showing my new design, it being understood that the remaining three sides are substantially the same as the side shown herein;

FIG. 2 is a top plan view,

FIG. 3 is a bottom plan view, and

FIG. 4 is a top perspective view thereof.

I claim:

The ornamental design for a variable resistor, as shown.
